SIFTER-CLOSURE FOR CONTAINER SELE-
TIVELY ATTACHABLE THERETO IN DIS-
PENSING OR NONDISPENSING POSITIONStanley F. S. Jones, Hamilton, Ontario, Canada,
assignor to American Can Company, New York,
N. Y., a corporation of New Jersey

Application December 12, 1946, Serial No. 715,722

6 Claims. (Cl. 222—480)

1

The present invention relates to a container or can having a cover which is transposable by removal and replacement into different positions for sealing the can and for bringing sifter holes into register for sifting the contents of the can and has particular reference to elements for insuring proper register of the sifter holes for a sifting operation and for insuring sifter-proof sealing between the can and the cover when the sifter holes are out of register.

An object of the invention is the provision of a sifter top can having a transposable cover wherein proper alignment of sifter holes in the cover and in the can may be rapidly and easily effected by a mere removal and replacement of the cover.

Another object is the provision of such a can wherein locating elements formed in the cover and in the can insure the proper alignment of the sifter holes upon placement of the cover and without any further adjustment.

Another object is the provision of such a can wherein a sifter-proof seal is effected between the cover and the can when the cover is in can sealing position, so that the content of the can is prevented from sifting out through the joint between the can and the cover.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a sifter top can embodying the instant invention;

Fig. 2 is an exploded perspective view of the can shown in Fig. 1, with the cover of the can disposed in spaced relation to the can top and with the lower portion of the can being broken away; and

Figs. 3, 4 and 5 are enlarged sectional views taken substantially along the planes indicated by the lines 3—3, 4—4 in Fig. 1, Fig. 5 being a view similar to Fig. 4 with the cover in a different position.

As a preferred embodiment of the invention the drawings illustrate a well known cylindrical type of sheet metal sifter can for spice or condiments. The can comprises a tubular body 11 with a closed bottom and having a top or friction ring 12. Both bottom and top are permanently secured to the body in suitable seams 13.

The top or friction ring 12 preferably is of the countersunk type having a flat panel wall 14 in-

2

wardly of the seam 13. The panel wall is formed with a slightly raised continuous shoulder 15 having a depending flange 16 which defines a cylindrical friction seat for a removable closure member or friction cover 18. The depending flange 16 merges into two oppositely disposed substantially horizontal and spaced shelves or plate elements 21, 22 which between them set off a narrow rectangular slot or dispensing opening 23 through which the contents of the can may be dispensed in bulk form when the cover is removed.

The dispensing opening 23 preferably extends across the can top from one side of the flange 16 to its opposite side. The shelf 21 is imperforate while the shelf 22 is formed with a group of sifter perforations or holes 25. The inner edges of the shelves or plate elements are curled downwardly as best shown in Fig. 4. This provides smooth curved auxiliary friction seats 26.

The friction cover 18 preferably is circular and is formed with a horizontal bottom panel 31 which merges, at its outer periphery, into a substantially vertical upright friction wall 32. This friction wall is adapted to fit tightly within the friction seat provided by the depending flange 16 of the friction ring 12 when the cover is in place on the can. The top edge of the friction wall 32 is bent outwardly and thence downwardly and back on itself and thus provides a smooth hem 33 which may be utilized as a gripping or hand hold element when applying the cover to the can or as a prying element when removing it.

The bottom panel 31 of the cover 18 is formed with a rectangular shaped depressed or countersunk locating member or boss 35 which extends completely across the cover from one side of its upright wall 32 to the opposite side. The locating member 35 is formed with a curved bottom wall 36 which at its ends merges into short extensions 37 of the upright wall 32 (see Fig. 3). Along its sides, the curved bottom wall 36 merges into upright wall sections 38 which in turn merge into the bottom panel 31 of the cover.

When the cover is in place on the can, the locating member or element 35 extends down into the dispensing opening 23 of the friction ring 12, as best shown in Figs. 3 and 4. The extensions 37 of the upright wall 32 of the cover at the ends of the locating member engage tightly against the flange 16 of the friction ring 12 while the side or upright wall sections 38 of the locating member engage tightly against the smooth friction seats 26 of the ring. In this manner a double friction seal is provided for the cover, one seal being ef-

fected between the upright wall 32 of the cover and the flange 16 of the ring, and the other or auxiliary seal being effected between the locating member and the ring.

Provision is made for utilizing the cover 18 as a sifter top, as hereinbefore mentioned. For this purpose the bottom panel 31 of the cover on one side of the locating member 35, is cut through with sifter perforations or holes 39 (Figs. 2 and 4). This group of holes is similar to the group of holes 25 in the friction ring plate shelf 22, the holes in the two groups having the same place arrangement. The opposite side of the bottom panel 31 of the cover is imperforate.

In one position of the cover 18 on its friction seat flange 16, as shown in Fig. 5, the sifter holes 39 of the cover are adjacent the imperforate shelf 21 of the friction ring 12. In this position the imperforate portion of the cover is adjacent the perforated shelf 22 having the sifter holes 25. In this position of the cover the can is effectively sealed since both the dispensing opening 23 and the sifter holes 25 in the ring are closed or blocked off and escape of the contents of the can is prevented. The double friction seats 16, 26 of the ring furthermore prevent sifting through these joints of any of the contents as will be apparent.

In another position of the cover 18, the sifter holes 39 of the cover are brought into register with the sifter holes 25 in the shelf 22 of the friction ring 12. The aligned sifter holes 25, 39 provide for communication with the interior of the can and its contents may be freely dispensed through these perforations. This bringing of the sifter holes into register is effected by merely removing the cover from its sealing position. Then it is turned around to bring its sifter holes on the opposite side whereupon the cover is again frictionally applied.

In order to replace the cover in an easy manner, the locating element 35 is inserted in the dispensing opening 23 of the ring 12. The locating element is made deep enough so that it will enter the dispensing opening before any contact is made of the cover upright wall 32 with the seat flange 16. This entry of the locating element into the dispensing opening aligns the sifter holes 39 of the cover with the sifter holes 25 in the ring and thus provides for exact register of these holes when the cover is forced down tightly onto its seat flange 16. In this manner the locating element 35 serves as a fool-proof guide for properly and easily replacing the cover in a sifter position or in a sealing position on the can.

When it is desired to dispense the contents of the can in bulk form, it is merely necessary to remove the cover and leave it off. This exposes the dispensing opening 23 and permits the insertion of a spoon or other tool into the can for removal of its contents.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container having an elongated dispensing opening disposed between two plate elements for bulk removal of the contents of the container,

said container having a plurality of sifter holes in one of said plate elements adjacent said dispensing opening for sifting the contents of the container and having smooth sealing edges adjacent said dispensing opening, a cover having a panel wall for sealing engagement with said plate elements, a corresponding plurality of sifter holes therein, said cover being adapted for removal and replacement into different positions on said container with its panel wall engaging said plate elements, in one such position the sifter holes of the cover being out of register with the sifter holes of the container for closing the container and in another position with the sifter holes of both parts in register and providing communication with the interior of the container for sifting its contents, and an elongated countersunk locating member formed in said cover and insertable into the dispensing opening in said container in tight fitting engagement with the sealing edges adjacent said dispensing opening for locating and insuring register of said sifter holes for a sifting operation.

2. A container having an elongated dispensing opening with parallel long sides for bulk removal of the contents of the container, said container having a plurality of sifter holes therein adjacent one of the long sides of said dispensing opening for sifting the contents of the container, a friction seat in said container and surrounding said dispensing opening and said sifter holes, a cover having a corresponding plurality of sifter holes located on one side of its center, said cover being adapted for removal and replacement into two different positions while seated with its sifter holes on different sides of said dispensing opening in the friction seat of said container, in one such position the sifter holes of the cover being out of register with the sifter holes of the container for closing the container and in the other position with the sifter holes of both parts in register and providing communication with the interior of the container for sifting its contents, and elongated locating means with parallel long sides in said cover and insertable into the dispensing opening in said container for locating the cover in its different positions.

3. A container having a friction seat therein, a countersunk imperforate plate element disposed within said friction seat, a countersunk perforated plate element having a group of sifter holes therein also disposed within said friction seat and located opposite said imperforate plate element, said plate elements setting off between them an elongated dispensing opening for bulk removal of the contents from said container, a cover having a friction wall for engagement with said friction seat and a bottom panel wall for sealing engagement with said plate elements and a group of sifter holes in said panel wall, said cover being adapted for removal and replacement into different positions on the friction seat of said container, in one such position the sifter holes of the cover being out of register with the sifter holes of said perforated plate element for closing the container and in another position with the sifter holes of both parts in register and providing communication with the interior of the container for dispensing its contents, and an elongated countersunk locating member formed in said cover and insertable into the dispensing opening in said container and in sealing engagement between said plate elements and the cover panel wall for locating the cover in the desired position.

4. A container having a cylindrical friction wall

5

seat, a shelf disposed at the base of said friction wall seat and cut through by a non-circular dispensing opening, said shelf having a plurality of sifter holes located inside of said seat for sifter dispensing of the contents of the container, a cover having a cylindrical friction wall for engagement with the cylindrical friction seat of said container and having a corresponding plurality of sifter holes, said cover being adapted for removal and for frictional replacement into different positions on the container, and non-circular locating means formed in the cover and selectively fitting inside of said dispensing opening for locating the cover in a replaced position either to close the container against sifting of its contents or to provide for sifting dispensing.

5. A container having a symmetrical non-circular dispensing opening formed in a wall thereof, sifter perforations in said wall adjacent one side of said opening, a cover for said container having a panel wall for close engagement with said container wall said cover having a countersunk locating boss in shape substantially the counterpart of said container dispensing opening for closely fitting within the opening in different closure positions, and sifter perforations in said cover panel wall at one side of said countersunk boss for registering with the container wall perforations when the cover is in one of its closure positions said cover perforations being out of register with the container perforations and located directly over an imperforated portion of said container wall in another of its closure positions for closing the container.

6

6. A container having an elongated dispensing opening and a plurality of sifter holes located on one side of said dispensing opening, a sealing element surrounding said opening and said sifter holes, a cover having a sealing element engageable with said container sealing element, said cover also having a plurality of sifter holes and being adapted for removal and replacement into different positions on said container, in one such position the sifter holes of said cover being out of register with the sifter holes of said container for closing said container and in another position with the sifter holes or both parts in register and providing communication with the interior of the container for sifter dispensing of its contents, a boss formed in said cover for selective engagement within said elongated dispensing opening with the sealing elements of said cover and container in sealing engagement, said boss sealing said dispensing opening and preventing escape of the contents of said container through the dispensing opening when said cover is in either sifting or closing position on said container.
